UNITED STATES PATENT OFFICE.

FRED A. DENNETT, OF SHEBOYGAN, WISCONSIN.

DESIGN FOR A VENEER-PRESSING MEMBER.

SPECIFICATION forming part of Design No. 34,943, dated August 13, 1901:

Application filed March 28, 1901. Serial No. 53,370. Term of patent 14 years.

To all whom it may concern:

Be it known that I, FRED A. DENNETT, a citizen of the United States of America, residing at Sheboygan, in the county of Sheboygan and State of Wisconsin, have invented and produced a certain new, useful, and original Design for an Article of Manufacture—to wit, a Veneer-Pressing Member—of which the following is a specification, reference being had to the accompanying drawings, forming a part hereof.

In said drawings, Figure 1 is a plan view of a veneer-pressing member embodying my design. Fig. 2 is a longitudinal sectional view taken on line 2 2 in Fig. 1. Fig. 3 is a cross-sectional view taken on line 3 3 in Fig. 2. Fig. 4 is a cross-sectional view taken on line 4 4 in Fig. 1, these four views being deemed necessary for full illustration.

The leading and essential feature of my design for a veneer-pressing member consists of the peculiar and novel formation of the upper surface of the same, which is rectangular and bounded by the lines $h\ i$, $i\ j$, $j\ k$, and $k\ h$ and provided with a depressed portion, hereinafter referred to. The depressed portion proceeds inwardly from points $a\ a$, one in each side, to points $b\ b$ on curved lines, from the points $b\ b$ to points $c\ c$ on substantially straight lines substantially parallel with the side $h\ i$ and $j\ k$, respectively, and from points $c\ c$ around on a semicircular line touching the point d . The upper surface bounded by the straight edges $a\ i$, $i\ j$, and $j\ a$ and the curved line $a\ d\ a$ is in one plane. Located at the center of the depressed portion and ex-

tending from the front edge $h\ k$ substantially to the center of the upper surface is a mound or raised portion e , the top of which, which lies above the flat surface before described, is highest at the front edge and from there proceeds back on a line sloping gradually to a point beyond the center of the upper surface. From the semicircular boundary-line $c\ d\ c$ of the depressed portion the depressed portion slopes inwardly on curved surfaces toward the inner end of the raised portion e . From an imaginary straight line joining the points $d\ a$ across the design the depressed portion on each side of the raised portion e slopes gradually toward the rear and toward the front edge and the front corners of the design carrying with them the edges $h\ a$ and $k\ a$ of the design.

The several minor features of my design for a veneer-pressing member may be stated as follows: The bottom is flat and its plane is parallel with the plane of the flat portion of the upper surface. The sides are parallel planes and stand at right angles to the bottom, as do the ends.

Having thus described my design, what I claim is—

The design for a veneer-pressing member, substantially as shown and described. 65

Signed by me this 21st day of February, A. D. 1901.

FRED A. DENNETT.
